SALES DEMONSTRATOR FOR ROTATABLE SHELVES

Paul H. Frick, Wynnewood, Pa., assignor to The Frick - Gallagher Manufacturing Company, Wellston, Ohio, a corporation of Ohio

Application March 14, 1950, Serial No. 149,609

5 Claims. (Cl. 35—50)

1

This invention relates to demonstration devices and is more particularly concerned with the provision of a device which is adapted to demonstrate to prospective customers the savings in floor space which may be effected by the use of so-called rotary bins or shelves in contrast to the conventional type of rectangular shelves.

The general object of this invention is to provide, in miniature, a model of a typical floor space containing a plurality of rows of rectangular shelf units with aisles therebetween and means for readily collapsing the model to demonstrate the saving in space when rotatable bins or shelf units are substituted for the rectangular units.

It is also an object of the invention to provide means for showing the location of rotatable units relative to the rectangular units of the collapsed model.

The device of the present invention is particularly useful for salesmen attempting to interest prospective customers to purchase rotatable bins and in this respect provides a graphic illustration of the advantages thereof which is much more effective and much more readily understood than complicated mathematical figures intended to accomplish the same result.

Accordingly, a further object of the invention is the provision of such a device which can be readily carried about by a person from place to place and particularly by itinerant salesmen.

A still further object is the provision of a device of the type mentioned which is simple in construction, easy to manufacture and not likely to become damaged under conditions of repeated handling.

These and other objects and advantages of the invention will be apparent from the following description considered together with the accompanying drawings, in which:

Figure 1 is a top plan view of an embodiment of the invention with the movable members thereof in their fully extended positions;

Figure 2 is a side elevational view of the same embodiment in the extended position;

Figure 3 is a cross sectional view along the line 3—3 of Figure 1;

Figure 4 is a top plan view similar to Figure 1 with the movable members in collapsed position and with shields disposed on said members to indicate the positions of the rotary bins;

Figure 5 is a side elevational view of the embodiment in the collapsed position;

Figure 6 is an isometric view of one of the shields included in Figures 4 and 5.

2

Referring with more particularity to the drawing in which like numerals designate like parts, the embodiment illustrated comprises a rectangular frame 11, having side strips 12, 12 and end strips 13, 13 which define a given storage area. To the bottom of the frame there is secured a base member 14. Each side strip 12 is provided with a groove or recess 15 and each end strip 13 is provided with a groove or recess 16 on the inside of the frame.

Within the area of the base 14 delineated by the frame strips there are disposed a plurality of members in parallel spaced relation representing to scale units of rectangular type shelves and the aisles therebetween. The end members 17 and 18 represent single row units while the intermediate members 19 represent double row units. Each of the members 17, 18 and 19 are secured to a glider disposed on top of the base

20 14 and extending on either side into the recesses 15 of the side strips. Some of the gliders, such as the gliders 20, have a width equal to the width of their shelf units 19. At intervals some of the gliders, such as the gliders 21, are wider than their corresponding shelf members to represent aisle space not eliminatable. In other words, substitution of the rotary shelf units permit elimination of some of the aisles, but not all. Accordingly, the wide gliders are provided at the points where the aisles cannot be eliminated. The location of these wider glide members depends upon the particular demonstration desired, that is to say, whether the demonstration will provide for single or double rows of rotary shelves or combinations thereof. The embodiment illustrated is for a combination of two single rows of rotary bins and two double rows of rotary bins, the single row being equivalent in capacity to the single rows of rectangular shelves and the double rows being equivalent in capacity to six single rows or three double rows of rectangular shelves.

The sides of the members 17, 18 and 19 are preferably delineated to pictorially represent the rectangular shelves. (See Figure 3.)

45 The members 17, 18 and 19 are maintained in proper relation to each other in their extended positions as illustrated in Figure 1 by means of flexible connectors 22 and 23 on either side, which are attached to the corresponding outer ends of said members by any suitable means, such as pins 24. At one end of the device, say the end where the member 18 is disposed, the flexible members 22 and 23 are anchored to the frame 11 by means 50 of tacks, or screws 25 or any other suitable means.

The elements 17, 18 and 19 are thus maintained in proper spaced relation when extended without interfering with the collapsing thereof.

To demonstrate the saving of space which obtains from the substitution of rotary units, the members 17, 18 and 19 are collapsed by moving the free member 19 at one end toward the opposite member 17. The collapsed position of the members is illustrated in Figures 4 and 5 which shows four separate collapsed groups consisting of two single row groups at the ends and, intermediately two double row groups. Shields in the form of inverted channels 26 are placed over each of the collapsed groups. Each of said shields has a width corresponding to the group on which it is to be placed and carries on the surface thereof delineations or illustrations of rotary shelf units which are substitutable for the collapsed group. These shields also prevent the expansion of the model during this part of the demonstration.

I claim:

1. A sales demonstrator for rotatable shelves comprising a frame defining a model of a storage area, a plurality of spaced members within the frame area, said members representing rows of rectangular shelving units, means for slidably supporting said members in said area, means for maintaining not less than a fixed spaced relation between some of said members and a flexible connector secured at intervals to said members.

2. A sales demonstrator for rotatable shelves comprising a frame defining a model of a storage area, a plurality of spaced members within the frame area, said members representing rows of rectangular shelving units, means for slidably supporting said members in said area, means for maintaining not less than a fixed spaced relation between some of said members, a flexible connector secured at intervals to said members and means for attaching one end of said connector to said frame.

3. A sales demonstrator for rotatable shelves comprising a frame defining a model of a storage area, a plurality of spaced members within the frame area, said members representing rows of

rectangular shelving units, means for slidably supporting said members in said area, means for maintaining not less than a fixed spaced relation between some of said members, a flexible connector secured at intervals to said members, means for attaching one end of said connector to said frame, whereby said members may be collapsed so as to eliminate the space between some of them and thereby provide a plurality of groups of the members, and shields adapted to be removably disposed about said groups, said shields representing the relative space occupied by rotatable shelves of comparable capacity.

4. A sales demonstrator for rotatable shelves comprising a frame defining a model of a storage area, a plurality of spaced members representing rows of rectangular shelving units, strips secured to said units for slidably supporting said members in said area, said frame having longitudinal recesses for receiving the ends of said strips, some of said strip being wider than their corresponding members to represent non-eliminatable aisle space and a flexible connector secured at intervals to said members and to said frame.

5. A sales demonstrator for rotatable shelves comprising a frame defining a model of a storage area, a plurality of spaced members representing rows of rectangular shelving units, strips secured to said units for slidably supporting said members in said area, said frame having longitudinal recesses for receiving the ends of said strips, some of said strips being wider than their corresponding members to represent non-eliminatable aisle space, a flexible connector secured at intervals to said members and to said frame, whereby said members may be collapsed so as to eliminate the space between some of them and thereby provide a plurality of groups of the members, and shields adapted to be removably disposed about said groups, said shields representing the relative space occupied by rotatable shelves of comparable capacity.

PAUL H. FRICK.
